UNITED STATES PATENT OFFICE.

HARRY LEVINE, OF CHICAGO, ILLINOIS.

FINISHING-MACHINE.

1,104,683.

Specification of Letters Patent.

Patented July 21, 1914.

Application filed July 11, 1913. Serial No. 778,477.

To all whom it may concern:

Be it known that I, HARRY LEVINE, a subject of the Czar of Russia, and a resident of the city of Chicago, county of Cook, and State of Illinois, have invented certain new and useful Improvements in Finishing-Machines, of which the following is a specification.

My invention relates to improvements in finishing machines especially adapted for use in finishing the edges of leather for making traveling bags and the like, the object of the invention being to provide an improved machine of this character, which is of simple construction and efficient in use.

The invention consists in the combinations and arrangements of parts hereinafter described and claimed.

The invention will be best understood by reference to the accompanying drawings forming a part of this specification, and in which—

Figure 1 is a side elevation of a machine embodying the invention and shown partially in section and with portions broken away, Fig. 2, a section taken on line $\alpha-\alpha$ of Fig. 1.

The preferred form of construction as illustrated in the drawings comprises a rotatable spindle 1 suitably mounted in a suitable standard 2 and provided with a suitable driving pulley 3 as will be readily understood. Spindle 1 is provided at one end with a slitting wheel 4 which cooperates with an adjustable support and guide 5 to facilitate the trimming of the edges of leather articles or the like. Inking wheels 7 and 8 are mounted on the other end of spindle 1 adjacent standard 2 and operate in inking housings 9 as indicated. The inking housing 9 is divided by a central partition 10 into two compartments each containing an absorbent pad 11 of sponge or other suitable material. Each of the pads 11 is retained in position by means of a retaining plate 12 which is hinged at 13 to one of the corresponding housings 9 and is provided with a spring catch 14 at the other side of said housing, each of said plates 12 being

slotted at 15 to permit the corresponding inking wheel to engage a pad 11. Each of the compartments in housing 9 is provided with a separate removable cover 16 which has an entry slot 17 in its top to give access to the corresponding inking wheel. By this arrangement it will be observed that inks of different colors may be placed in the compartments in the housing 9 and the edges of leather pieces readily inked or stained as desired. The specific arrangement of parts will supply ink to the inking wheels without permitting spattering of the same.

On the opposite walls of the removable cover 16 are depending ears 18 frictionally engaging sockets 19 carried on corresponding side walls of housing 9 serving as a means for locking the cover 16 in operative position.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A machine of the class described comprising a spindle; an inking wheel on said spindle; a housing surrounding said wheel and having a slot giving access thereto; a pad of absorbent material in the bottom of said housing in contact with said wheel; a hinged and slotted plate holding said pad in position to permit said inking wheel to engage the latter; and a spring catch for said plate, substantially as described.

In testimony whereof I have signed my name to this specification in the presence of two subscribing witnesses.

HARRY LEVINE.
